COLLAR CLASP

Louis Madison, New York, N. Y.

Application June 20, 1936, Serial No. 86,294

2 Claims. (Cl. 24—81)

This invention relates to collar clasps. It is particularly directed to a clasp for adjacent edges of a collar and located beneath the knot of a four-in-hand tie on said collar.

5 An object of this invention is to provide a collar clasp of the character described, having means to receive the adjacent edges of the collar and means for clamping said edges after the latter have been inserted into the clasp, the construction being such that the clamping means will remain in clamped condition until manually released.

10 A further object of this invention is to provide a collar clasp of the character described, having 15 highly improved means for drawing the edges of a collar together.

A still further object of this invention is to provide a neat, compact and durable collar clasp of the character described, which shall be relatively inexpensive to manufacture, easy to assemble and manipulate, and which shall yet be practical and efficient to a high degree in use.

Other objects of this invention will in part be obvious and in part hereinafter pointed out.

25 The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

30 Fig. 1 is a side elevational view of a collar clasp embodying the invention;

Fig. 2 is a top plan view of the clasp shown in Fig. 1, with parts in cross-section;

Fig. 3 is a side elevational view of a collar clasp embodying the invention and illustrating a modified construction; and

Fig. 4 is a top plan view of the structure shown in Fig. 3.

Referring now in detail to the drawing, 10 designates a collar clasp embodying the invention for engaging the adjacent edges of a collar and usually located beneath the knot of the four-in-hand tie on said collar. The clasp 10 comprises a curved member 11 symmetrical about the mid-portion thereof. Said member 11 is formed adjacent the outer ends thereof and on the outer surface thereof with serrated portions 12 for the purpose hereinafter appearing.

Attached to the mid-portion of the member 11, as by looped strap 14, is a member 15 symmetrical about the mid-portion thereof and having a

central offset portion 16 contacting the member 11. Said member 15 is substantially of the same length as the member 11 and has on opposite sides of the mid-portion 16 thereof, portions 17 parallel to the outer ends of member 11. It will be noted that the loop 14 is disposed about the portion 16 of the member 15 and the mid-portion of the member 11, and firmly attaches said member 11 to said member 15. There is thus formed between the member 11 and the portions 17 of 10 the member 15, slots 18 into which may be inserted the adjacent edges of a collar. The slots 18 are preferably sufficiently wide to permit the edges of the collar to be readily inserted without crimping or pinching the collar.

Means is provided for clamping the inserted portions of the collar to the clasp. To this end, each portion 17 of the member 15 is formed with a through slot 20 and with a vertical groove 21 of curved cross-section on the outer surface thereof of adjacent the inner end of the slot. A vertical pin 22 is disposed adjacent the outer end of each of said slots. Pivoted to each pin 22 and extending through the slot 20, is a lever 23 having a vertical curved handle portion 24 at one end adapted 20 to be received within the groove 21. The lever 23 has on the side of the axis thereof, opposite to the side on which the handle 24 is located, a projection 25 projecting into the slot 18 when the handle 24 is within the groove 21. When the 30 levers 23 are moved to positions at right angles to the portions 17 in the member 15, no portion of the levers projects into the slot 18. Thus, before inserting the edges of a collar into the slots 18, the levers 23 are moved to the position shown 35 in full lines at the right of Fig. 2, to clear the slots and permit insertion of the collar edges thereinto. After the collar edges have been inserted into the slots, the levers 23 may be swung or pivoted inwardly to bring the handle portions 40 24 thereof into the grooves 21, the portions 25 moving into the slots 18 and pressing the collar edges against the serrated portions 12 for firmly gripping the collar edges.

It will be noted that when the levers are in 45 gripping position, there will be pressure on the projection 25 in such direction that the levers will remain in closing position, as shown on the left of Fig. 2. When it is desired to remove the clasp from the collar, the levers are swung outwardly about their axes to release the collar edges.

It will be noted that the groove 21 permits the handles 24 to be engaged by a finger nail to facilitate manipulation of the levers. Furthermore, 55

the handles 24 preferably project somewhat above and below the portions 17 of the member 15 to further facilitate the manipulation of the levers.

5 In Figs. 3 and 4, there is illustrated a modified form of the invention. The clasps 10a shown in Figs. 3 and 4 comprise a pair of similar, symmetrically disposed members 30, having parallel spaced portions 31 and outwardly extending 10 curved portions 32. The portions 31 are formed with aligned, oppositely threaded openings 33 receiving therethrough a turnbuckle screw 32 provided with oppositely threaded end portions having conical ends 39. A finger wheel 35 is 15 fixed on the middle of the screw. The bottom ends of the portions 31 are formed with curved grooves 36, slidably receiving a bar 31 of curved cross-section. Said bar has at the outer ends thereof, upwardly extending arms 37 formed 20 with conical sockets 38 on the inner surfaces thereof, receiving conical ends 39 of the screw 34.

It will now be understood that as the wheel 35 is rotated, the members 30 will be moved toward or away from each other, depending upon 25 the direction of rotation. Extending upwardly from the member 37 and disposed between the handle 35 and the portions 31 of the members 30, are a pair of upstanding arms 40, preferably having grooves 41 of curved cross-section at their 30 upper ends, forming half bearings for the screw 34.

The portions 32 of the members 30 each have a longitudinal slot 45 to receive an edge of a 35 collar. The provision of the slot 45 divides each arm 32 into spaced parallel portions 46 and 47. The portion 46 has on the inner surface thereof and adjacent the outer end thereof, a serrated portion 48. Each portion 47 is provided with a through slot 50. A pin 51 crosses said slot at 40 one end; and a curved groove 48 is formed on portion 47 adjacent the other end of said slot. Pivoted within each slot 50 is a lever 23a similar 45 to lever 23 and likewise formed with projections for pressing the collar edges against the serrated surfaces or portions 48.

It will now be understood that the levers 23a are first opened to permit the edges of the collar to be inserted into the slots 45. The levers are

then swung inwardly to closing or gripping position, and the handwheel 35 is then rotated to adjust the distance between the collar edges.

It will thus be seen that there is provided a device in which the several objects of this invention are achieved, and which is well adapted to meet the conditions of practical use.

As various possible embodiments might be made of the above invention, and as various changes might be made in the embodiment above 10 set forth, it is to be understood that all matter herein set forth or shown in the accompanying drawing is to be interpreted as illustrative and not in a limiting sense.

Having thus described my invention, I claim as 15 new my desire to secure by Letters Patent:

1. A collar clasp comprising a pair of similar, symmetrically disposed members, having parallel portions and outwardly extending portions, said parallel portions being formed with aligned 20 oppositely threaded openings, a turnbuckle screw extending through said openings and having oppositely threaded end portions engaging the threads of said openings, a finger wheel fixed to the center of said screw, a member having sliding engagement with said parallel portions and having arms at the ends thereof rotatably engaging the ends of said screw, the outwardly extending portions of said members being formed with slots to receive the adjacent edges of a collar, and levers pivoted on said portions and adapted to clampingly engage collar edges inserted into said slots.

2. A collar clasp, comprising a member, a pair of symmetrically disposed members slidably and 35 non-rotatably mounted thereon and having oppositely threaded openings, a turn-buckle screw rotatably and non-slidably mounted on said first member and having oppositely threaded portions 40 engaging within said oppositely threaded openings, a finger wheel fixed to the mid portion of said turn-buckle screw, said pair of members being slotted to receive edge portions of a collar, and levers pivoted to said members and adapted to clamp said edge portions within said 45 slots.

LOUIS MADISON.
